UNITED STATES PATENT OFFICE.

JOHN F. BRASS, OF DOWNTON GROVE, ILLINOIS.

SPRINKLER-HEAD.

1,313,787.

Specification of Letters Patent. Patented Aug. 19, 1919.

Application filed July 9, 1917. Serial No. 179,337.

To all whom it may concern:

Be it known that I, JOHN F. BRASS, a citizen of the United States, residing at Downers Grove, in the county of DuPage and State of Illinois, have invented certain new and useful Improvements in Sprinkler Heads, of which the following is a specification.

My invention relates to sprinkler heads for automatic fire sprinkler systems and the object thereof is to provide a simple, efficient and reliable device of this kind, characterized more particularly by the employment of a valve support comprising two arms, each of which consists of two members normally held together by fusible solder and one being adapted to tilt, and also consisting of a link connecting said tilttable members.

In the drawing Figure 1 is an elevation of a sprinkler head embodying my invention; Fig. 2 a vertical central section on the line 2—2 of Fig. 1; Fig. 3 a top plan view of one of the members of the upper arm; Fig. 4 a similar view of the other member; Figs. 5 and 6 side elevations of the members shown in Figs. 3 and 4 respectively; Figs. 7 and 8 top plan views of the members of the lower arm; and Fig. 9 a cross-section on the line 9—9 of Fig. 2.

The sprinkler head comprises as usual the frame or yoke 1 having a nozzle opening 2 normally closed by the valve 3, a deflector 4 which, in the present case, is provided with a central screw-threaded stem forming the adjusting screw 5, and a valve support interposed between this screw and the valve for the purpose of holding the latter on its seat. My invention pertains to the valve support which is constructed as follows:

The valve support comprises two similar arms or levers pivoted on each other at their inner ends and extending outwardly at an angle to each other, one of the arms being in pivotal contact with the valve and the other with the screw. Each arm consists of two members 6 and 7 normally held together by means of fusible solder, the member 7 being tilttable on the other member and these two tilttable members being connected together by a rigid link 8. The member 6 comprises a flat or plate portion 6^a and a right-angled rib 6^b extending therefrom and running longitudinally of the arm. The upper arm is provided with a depending pivot edge 6^c adapted to fit in the socket

6^d of the lower arm. Each tilttable member 7 is bifurcated by reason of the slot 7^a extending part way of the length thereof whereby such member is adapted to straddle the rib 6^b of the other member. The outer end of the member 7 is provided with a transverse notch 7^b adapted to receive the link 8. When the parts are in their normal position the members 6 and 7 are held together against the strain caused by the screw 5 by fusible solder 7^c applied to the adjacent portions of such members 6 and 7, but when such solder is melted by the heat of a fire the member 7 will tilt and the member 6 being thereby no longer restrained, will fly loose and will be thrown free of the sprinkler head, thereby permitting the valve to be forced from its seat in the usual and well known manner. The link 8 is a rigid link, as distinguished from a fusible link and serves, in conjunction with the fusible solder, to resist the tension exerted by the arms or levers.

I prefer to provide these arms on opposite sides with projections 6^e, which are adapted to contact the side arms of the yoke when the valve support is swung over to one side or the other, thereby preventing such support from coming into full contact with the yoke, and consequently interfering with the sensitiveness of the head.

I claim:

1. A sprinkler head comprising a head having a nozzle opening, a valve governing such opening, and a valve support consisting of two similar arms pivoted on each other and each including two members, one adapted to tilt on the other but normally restrained by fusible solder, and a link connecting said two tilttable members.

2. A sprinkler head comprising a head having a nozzle opening, a valve governing such opening, and a valve support consisting of two similar arms pivoted on each other and each including two members, one adapted to tilt on the other but normally restrained by fusible solder, and a rigid link connecting said two tilttable members.

3. A sprinkler head comprising a head having a nozzle opening, a valve governing such opening, and a valve support consisting of two similar arms pivoted on each other and each including two members, one adapted to tilt on the other but normally restrained by fusible solder, said arms being pivoted on each other at their inner ends and

extending outwardly at an angle to each other, and a link connecting the outer ends of the arms.

4. A sprinkler head comprising a head having a nozzle opening, a valve governing such opening, and a valve support consisting of two similar arms pivoted on each other and each including two members, one being bifurcated part way of its length to straddle a portion of the other and adapted to tilt on such other member but normally restrained by fusible solder, and a link connecting said two tilttable members.
5. A sprinkler head comprising a head having a nozzle opening, a valve governing such opening, and a valve support consisting of two similar arms pivoted on each other and each including two members, one

having a plate portion and a right angled rib thereon and the other being bifurcated 20 part way of its length to straddle said rib and adapted to tilt on said plate portion, and a link connecting said two tilttable members.

6. A sprinkler head comprising a head 25 having a nozzle opening, a valve governing such opening, and a valve support consisting of two similar arms pivoted on each other and each including two members, one adapted to tilt on the other but normally restrained by fusible solder, a link connecting 30 said two tilttable members, and a projection on one of the arms to contact the yoke in case the arms should swing toward the same.

JOHN F. BRASS.
